UNITED STATES PATENT OFFICE.

CHARLES S. PARSONS, OF BEVERLY, NEW JERSEY, ASSIGNOR TO FRANK W. WHITCHER, OF BOSTON, MASSACHUSETTS.

LASTING-PINCERS.

No. 868,695.

Specification of Letters Patent.

Patented Oct. 22, 1907.

Application filed December 4, 1903. Serial No. 183,717.

To all whom it may concern:

Be it known that I, CHARLES S. PARSONS, a citizen of the United States, residing at Beverly, in the county of Burlington, State of New Jersey, have invented a 5 certain new and useful Improvement in Lasting-Pincers, of which the following is a specification, reference being had therein to the accompanying drawings.

My invention has for its object an improvement in lasting pincers of the kind which are provided with 10 a hammer detachably connected with the lower jaw of the pincers.

In pincers of this class it is desirable that means be provided whereby the hammer head may be raised or lowered relatively to the pincer jaw, that is to say, 15 means by which an adjustment of the distance between the hammer face and the under side of the lower pincer jaw may be obtained. It is further desirable that the means employed for permitting this adjustment may be such that in case of breakage of the connection 20 between the hammer and the pincers, repairs may be effected at a minimum of expense.

Heretofore, lasting pincers of the kind above referred to have been constructed in which the hammer is provided with a screw-threaded shank or stud 25 formed integral therewith which is adapted to be screwed into a hole or recess in the lower pincer jaw, and such pincers have also been constructed with the threaded stud or shank integral with the lower jaw of the pincers and adapted to be screwed into a recess or 30 hole in the hammer head. In these forms of pincers vertical adjustment of the hammer has been obtained by the workman to suit his individual requirements by placing disks of leather or the like in the bottom of the hole or recess which is either in the pincers jaw or 35 hammer head, thus preventing the connecting shank or stud from being screwed home. When this is done the top of the hammer head and the lower jaw of the pincers have no bearing upon each other, but are separated and the strain on the hammer head in use is apt 40 to result in breakage of the connecting shank or stud. It also not infrequently happens that breakage of the shank or stud occurs when the hammer head and lower jaw of the pincers are in contact, that is when these parts bear properly upon each other. When breakage 45 of the shank or stud occurs in the construction above referred to, the hammer head or the lower jaw of the pincers requires to be discarded and replaced by a new one.

My present invention has for its object to provide 50 lasting pincers which shall combine the advantages of cheap and easy repair in case of breakage of the connecting shank or stud which unites the hammer head to the pincers while at the same time affording an opportunity for the employment of a means of vertical

adjustment of the hammer head by which the adjustment may be effected without lessening the strength of the device. 55

The vertical adjustment referred to and which is hereinafter more fully set forth forms the subject of another application for Letters Patent filed by me of 60 even date herewith.

My invention will be fully understood from the following description, reference being had to the accompanying drawings forming a part hereof and the novel features are pointed out and clearly defined in the 65 claims at the close of this specification.

In the drawings, Figure 1 shows a pair of lasting pincers with my invention applied thereto, the hammer head and connected parts being shown in section. Fig. 2 is a detail in section showing a modification hereinafter referred to. Fig. 3 shows a pair of lasting pincers embodying another modification of my invention, the hammer head and a portion of the pincer jaw being in section. Fig. 4 is a detail showing a modified form of connecting screw hereinafter described. 70

Referring to the drawings, *a* and *b* are the upper and under jaws respectively, of a pair of lasting pincers, the under jaw *b* is provided with a hole or recess *d* which is threaded for the reception of the threaded connecting stud *e*. The connecting screw-threaded stud or shank 80 *e* fits snugly in a threaded hole in the jaw *b*. The hammer head *f* may be of any desired shape and is provided with a hole *g* which is also screw-threaded for the reception of the lower end of the connecting stud *e*. The connecting stud *e* is in its simplest form, preferably 85 threaded throughout its length, as shown Fig. 1. The upper surface of the hammer *f* is faced off flat to furnish an extended bearing around the connecting stud *e* upon the lower surface of the under jaw *b* or upon interposed separating and reinforcing pieces shown at *i*. By making the connecting stud *e* an independent part not integral with either the pincer jaw or the hammer head, the said part *e* while insuring a secure connection between the jaw and the hammer head may in case of breakage, or for any other reason, be readily detached both from 90 the pincer jaw and from the hammer head. As the usual breakage which occurs is the breakage of the connection between the hammer head and the pincer jaw, the employment of an independent connection permits repair to be effected at a minimum of expense and with 100 very slight loss of time.

Combined with the feature of an independent connection as above described between the hammer head and the pincer jaw I provide for a simple and efficient means of vertical adjustment of the hammer head to 105 suit individual requirements without impairing the strength of the device. This I effect by means of separating reinforces which preferably surround the con-

nection *e* and are interposed between the pincer jaw and the top of the hammer head, see Fig. 1. The reinforces are provided with faces corresponding in shape or contour with the face of the lower jaw and the face of the hammer head respectively, in order that the proper bearing may be insured between the upper jaw, reinforce and hammer head. The diameter of the reinforce should be as great as may be obtained while at the same time insuring the bearing surface above referred to. The thickness of the reinforce may be varied but I prefer that they should be comparatively thin in order that a more accurate adjustment to individual requirements may be obtained. One or more of the said reinforces may be integral with the connections *e* if desired.

15 Hitherto lasting pincers have been constructed in which the top of the hammer head has been given a conical form and the hole in the pincer jaw for the reception of the hammer head shank or stud correspondingly counter-sunk. This modification increases the bearing 20 surface between the top of the hammer head and pincer jaw and tends to strengthen the connection.

At Fig. 2 I have shown my independent connection *e* applied to a pincer jaw and hammer head of the counter-sunk and conical form and I have also shown applied thereto a separating reinforce *h* corresponding to the reinforce *i* shown in Fig. 1, but having a conical form to fit between the counter-sink of the pincer jaw and the conical top of the hammer head. By the employment of one or more of these conical reinforces *h* the hammer 30 head may be vertically adjusted as required while the full bearing of the hammer head and the jaw and consequent strength of the construction is maintained.

In all forms of the invention employing the reinforces they closely surround or encircle the studs or shanks *e* 35 and are rigidly clamped between the bearing surfaces between which they are interposed so as to support said stud or shank against lateral strain.

At Fig. 3 still another modification of my invention is shown in which the independent connection *e* is provided with an annular collar or projection *j* which may be either integral with the connecting stud *e* as shown Fig. 3, or may be separated therefrom, as shown Fig. 4. The part *j* is formed with a conical upper face and a flat lower face, the conical upper face is received in a counter-sink in the face of the pincer jaw and the flat lower face is either directly in contact with the top of the hammer head or there may be interposed between said lower face and the top of the hammer head one or more separating reinforces *i* to provide a greater vertical adjustment of the hammer head. In this construction the independent connection is combined with the increased strength obtained from the conical top and counter sunk construction while at the same time vertical adjustment of the hammer head is permitted and

the full strength of the device maintained regardless 55 of the adjustment.

By the employment of my invention the cost of the usual repairs for lasting pincers of the class herein referred to is reduced to a minimum, while by having on hand duplicates of the inexpensive connecting stud 60 repair of the pincers when breakage occurs may be very quickly effected.

My improvement further in no wise interferes with the employment of the means set forth by which vertical adjustment of the hammer head may be obtained 65 to suit the requirements of any individual workman while at the same time retaining at all points of the adjustment the full strength of the connection between the hammer head and pincers.

What I claim is;

1. In lasting pincers, the combination of a jaw, a detachable hammer head, an independent detachable shank screwed into said jaw and connecting the said jaw and hammer-head, said shank having thereon an annular projection arranged between said jaw and hammer-head, and having a conical face bearing solidly against a counter-sunk face of said jaw, for the purposes and substantially as set forth.

2. In lasting pincers, the combination of a jaw, a detachable hammer head, an independent detachable shank screwed into said jaw and connecting the said jaw and hammer head, said shank having thereon an integral annular projection arranged between said jaw and hammer head for the purposes and substantially as set forth.

3. In lasting pincers, the combination of a jaw, a detachable hammer head, an independent detachable shank, having an annular projection thereon, said projection having a conical face bearing solidly against a countersunk face of said jaw, and reinforces around said shank interposed and rigidly clamped between the said annular projection and the said hammer head, substantially as described.

4. In lasting pincers, the combination of a jaw, a detachable hammer head, an independent detachable shank connecting said jaw and hammer head, a reinforce around and integral with said shank, said reinforce being clamped rigidly between and bearing solidly against said jaw and hammer-head and having a conical upper face fitting in a countersink in the jaw, and a flat lower face, said reinforce thus serving to separate said hammer-head and jaw and support the shank, substantially as described.

5. In lasting pincers, the combination of a jaw, a detachable hammer head, an independent detachable shank connecting said jaw and hammer-head, a reinforce around and integral with said shank, said reinforce having a conical upper face fitting into a countersink in the jaw, and a flat lower face, and one or more additional reinforces around said shank and rigidly clamped between said conical reinforce and said hammer-head, so as to support said shank, substantially as described.

In testimony whereof I affix my signature in presence of two witnesses.

CHARLES S. PARSONS.
